UNITED STATES PATENT OFFICE.

RODERICK W. RODERICK, OF AKRON, OHIO.

TRAFFIC-GUIDE.

1,123,925.

Specification of Letters Patent.

Patented Jan. 5, 1915.

Application filed January 27, 1914. Serial No. 814,635.

To all whom it may concern:

Be it known that I, RODERICK W. RODERICK, a citizen of the United States, residing at Akron, in the county of Summit and State of Ohio, have invented certain new and useful Improvements in Traffic-Guides, of which the following is a specification.

This invention relates to traffic guiding means and, with regard to certain more specific features thereof, to a stationary device adapted to be located at the intersection of two or more traffic paths.

One of the objects of the present invention is to provide a simple and practical device of the above character which will be cheap to manufacture and install.

Another object is to provide a device of the above character particularly adapted to be positioned at the intersection of two streets whereby it may be efficiently operated by the crossing policeman for regulating the traffic.

Other objects will be in part obvious and in part hereinafter pointed out.

The invention accordingly consists in the features of construction, combination of elements and arrangements of parts which will be exemplified in the device hereinafter described, and the scope of the application of which will be indicated in the following claims.

In the accompanying drawing, wherein is illustrated one of various possible embodiments of the present invention: Figure 1 is a semi-diagrammatic view of the complete device, certain parts being shown in section; Fig. 2 is a plan view of the device.

Similar reference characters denote corresponding parts in both views.

Referring now to the drawing and more particularly to Fig. 1 in which the present invention is shown as applied to the intersection of two streets, there are erected upon the opposite and diagonal corners supporting means, such as ornamental posts 5, having a cable 6 stretched between the upper portions. Suspended from this cable above the intersection of the streets is a casing 7, provided with a hood 8 adapted to protect it from the weather, as well as to protect illuminating lights 9 located around its four sides. The sides of this casing 7 are provided with advertising holding means, such as cleats 10 for holding removable cards. To the lower part of the receptacle and well above the path of traf-

fic are positioned three auxiliary receptacles 11, 12 and 13 respectively. These receptacles are preferably made with ground glass surfaces bearing legends thereon, such as "Fire," "Closed" and "Open," and are provided with illuminating means 14 and 15 therein, as shown more particularly in Fig. 2. The illuminating means are preferably ordinary electric lights, and may be wired in the manner shown and connected with switches or push buttons, whereby the lights may be turned on and off at will by the traffic policeman at the corner. These push buttons are preferably located in a casing 17 mounted on one of the posts.

In the present embodiment it will be noted the device is adapted for use where traffic normally has a right of way in a north and south direction, the east and west traffic being subservient thereto. This being the case when the north and south traffic is to be closed to permit east and west traffic both push buttons are pressed which will illuminate the signs on all four sides, so as to indicate that the north and south traffic is closed, and that the east and west traffic is open. On breaking the contacts by the push buttons or switches the lights are all extinguished, thus indicating that the north and south traffic has the right of way. In case of fire the upper push button 18 is pressed, which will illuminate sign 11 and simultaneously ring a bell 19 within the casing, which is connected by a shunt circuit from the main feed wire.

It is believed that the application and method of use of a device of this character is clear from the above description, and a further discussion thereof is unnecessary.

As many changes could be made in the above construction and many apparently widely different embodiments of my invention could be made, without departing from the scope thereof, I intend that all matter contained in the above description or shown in the accompanying drawing shall be interpreted as illustrative and not in a limiting sense.

Having thus described my invention what I claim and desire to secure by Letters Patent is:

1. In a traffic guiding device, in combination, supporting means adjacent the intersection of a plurality of paths of traffic, supporting posts located on the corners of intersecting streets, a casing suspended

from said posts adjacent the intersection, traffic directing means facing the intersecting streets, lights for illuminating said means and means on one of said posts for rendering said directing means visible.

2. In a traffic guiding device, in combination, supporting means adjacent the intersection of a plurality of paths of traffic, supporting posts located on the corners of intersecting streets, a casing suspended from said posts adjacent the intersection.

traffic directing means facing the intersecting streets, means for illuminating the entire device, and special means mounted on one of said posts adapted to illuminate pre-determined signs at will. 15

In testimony whereof I affix my signature in presence of two witnesses.

RODERICK W. RODERICK.
